United States Patent Office.

JOHN DAVID BROWNE, OF CINCINNATI, OHIO.

Letters Patent No. 82,286, dated September 22, 1868.

IMPROVED MOP-HEAD.

The Schedule referred to in these Letters Patent and making part of the same.

TO ALL WHOM IT MAY CONCERN:

Be it known that I, JOHN DAVID BROWNE, of the city of Cincinnati, county of Hamilton, and State of Ohio, have invented a new and useful Improvement in the Construction of Mop-Heads, the nature of which invention consists in the method of constructing and operating the loose or sliding jaw, and securing the material of the mop; and I do hereby declare that the following is a full, clear, and exact description of the construction and operation of the same, reference being had to the annexed drawings, making part of this specification, in which—

Figure 1 is a perspective view of the mop-head.

Figure 2 is a horizontal plan of the same.

Figure 3 is a view of the sliding jaw on section of nut.

To enable others skilled in the art to make and use my invention, I will proceed to describe its construction and operation.

A represents the fixed jaw, having a serrated edge, α , to hold the materials of the mop securely.

On the jaws A is cast the socket B, to receive the handle.

On the outside of the socket B are formed the threads of a screw, on which the nut C fits.

On the sides of the socket B are also made grooves or recesses $c c$, in which the ends $d d$ of the loose jaws D are guided.

D is the loose or sliding jaw, having the ends $d d$ formed so as to clasp the nut C and retain it in its place.

Operation.

By turning the nut C, the sliding jaw D is moved back and forth to grasp or release the materials of the mop.

What I claim, and desire to secure by Letters Patent, is—

The fixed jaw A, having the grooves or recesses $c c$ on the socket B, in combination with the loose jaw D $d d$ and nut C, substantially as and for the purpose described.

Also, in combination with the above, the serrated edges α on the jaw A, as set forth.

JOHN DAVID BROWNE.
